UNITED STATES PATENT OFFICE.

OSCAR W. PEDERSON, OF CHICAGO, ILLINOIS, ASSIGNOR OF ONE-HALF TO THOMAS F. RYAN, OF CHICAGO, ILLINOIS.

ORIFICE-FORMING CORE FOR CONCRETE FLOORS.

Application filed March 20, 1926. Serial No. 96,194.

This invention relates to a sectional core for forming an orifice or passage through a concrete floor during the process of molding the same in situ upon the usual temporary form or false work. And the present improvement has for its object:

To provide a structural formation and combination of parts in a sectional core of the tubular type, adapted for ready application and substantial attachment to the surface of the mold board upon which the floor is formed in situ, and at the location in which an orifice or passage is desired in the floor, all as will hereinafter more fully appear.

In the accompanying drawing:

Fig. 1 is a perspective view of the upper member of the present tubular core structure, in a detached condition.

Fig. 2 is a similar view of the lower member of the tubular core in a like detached condition.

Fig. 3 is a detail top view of the upper core member.

Fig. 4 is a similar view of the lower core member.

Fig. 5 is a detail section of the lower core member on line 5—5, Fig. 4.

Fig. 6 is a detail section of a portion of concrete flooring having the present core in place, with the upper and lower core members shown in section on line 5—5, Fig. 4.

Fig. 7 is a detail section similar to Fig. 6, and on line 7—7, Fig. 4.

Like reference numerals indicate like parts in the several views.

The present improvement is intended for use in connection with that class of concrete floors 1 which are molded in place upon a horizontal mold board or form 2 supported in position by the usual temporary frame or false work, and has for its purpose to afford a ready and substantial means for forming vertical orifices or passages through the concrete floor at points desired and during the molding of the floor.

To such end the present invention comprises an upper tubular member 3, preferably of a cylindrical form as shown, and having a length somewhat greater than the thickness of the concrete floor 1 with which it is associated. At its lower end the member 3 is formed with a plurality of outstanding lateral coupling ears or flanges 4 for in-

terlocking engagement with the fixed lower member of the appliance now to be described.

The base or socket member above referred to is of a disk shape and formed with a series of nail holes 6 by which it is firmly nailed to the mold or form 2 at the desired locations. In the present improvement said socket member is formed with a raised central crown or web 7 provided with a central orifice 8 adapted to receive and have a holding engagement with the lower end of the tubular member 3 aforesaid, and with the coupling lugs 4 of the upper member engaged beneath the margin of said orifice.

At intervals around the margin of the orifice 8, and in the margin thereof, a plurality of notches 9 are formed, with said notches having a complementary shape to that of the coupling lugs 4 of the upper tubular member 3, to permit downward passage of the lugs through said notches in an assembly of the two members of the appliance.

Adjacent to the notches 9, the margin of the central orifice 8 is formed with a plurality of inclined webs 10, underneath which the coupling ears 4 of the tubular member 3 ride to force said upper member downward against the upper surface of the form or mold board 2 to attain a rigid and substantial attachment of said upper member in proper vertical position.

In the preferred construction shown, the outer portion of the base or socket member is formed with a plurality of raised webs 11, alternating with the nail holes 6 of the same, and with each web 11 formed with apertures 12, for the entry of unset concrete below the webs 11 to insure an effective attachment of said base or socket member in place in the finished concrete floor, 1.

In practice, and during the formation of the concrete floor 1, the cavity of the upper tubular member 3 will be filled with sand or like loose material to prevent entry of any of the concrete material from which the floor is formed.

Having thus fully described my invention what I claim and desire to secure by Letters Patent, is:

1. In an orifice forming core for concrete floors, the combination of a plate metal socket member having nail holes for fastening the member in place upon a mold board

- said socket member having a central raised portion formed with a central orifice and with notches and inclined surfaces in the margin of said orifice, and an upper tubular core member the lower end of which passes through the central orifice of the socket member and is provided with outstanding flanges for engagement beneath the inclined surfaces in the margin of the aforesaid central orifice.
2. In an orifice forming core for concrete floors, the combination of a plate metal socket member having nail holes for fastening the member in place upon a mold board, said socket member having a central raised portion formed with a central orifice, and an upper tubular core member the lower end of which passes through the central orifice of said socket member and is provided with outstanding flanges for engagement beneath the margin of said orifice, the portion of the socket member surrounding its central

raised portion being formed with a series of raised and orificed webs.

3. In an orifice forming core for concrete floors, the combination of a plate metal socket member having nail holes for fastening the member in place upon a mold board, said socket member having a central raised portion formed with a central orifice and with notches and inclined surfaces in the margin of said orifice, and an upper tubular core member the lower end of which passes through the central orifice of the socket member and is provided with outstanding flanges for engagement beneath the inclined surfaces in the margin of the aforesaid central orifice, the portion of the socket member surrounding its central raised portion being formed with a series of raised and orificed webs.

Signed at Chicago, Illinois, this 18th day of March, 1926.

OSCAR W. PEDERSON.
